US0D1042334S

(12) **United States Design Patent** (10) Patent No.: **US D1,042,334 S**
(45) Date of Patent: ** Sep. 17, 2024

(54) **PORTABLE CHARGER**

(71) Applicant: **Zimi Corporation**, Wuxi (CN)

(72) Inventor: **Yong Xu**, Jiangsu (CN)

(73) Assignee: **Zimi Corporation**, Wuxi (CN)

(**) Term: **15 Years**

(21) Appl. No.: **35/516,088**

(22) Filed: **Dec. 16, 2022**

(80) **Hague Agreement Data**

Int. Filing Date: **Dec. 16, 2022**

Int. Reg. No.: **DM/226070**

Int. Reg. Date: **Dec. 16, 2022**

Int. Reg. Pub. Date: **Jan. 27, 2023**

(30) **Foreign Application Priority Data**

Jun. 28, 2022 (CN) 202230402915.0

(51) **LOC (14) Cl.** **13-02**

(52) **U.S. Cl.**

USPC **D13/108**

(57)

CLAIM

The ornamental design for a portable charger, as shown and described.

DESCRIPTION

2.1: Front

2.2: Back

2.3: Left

2.4: Right

2.5: Top

2.6: Bottom

2.7: Perspective

1 Claim, 6 Drawing Sheets
